CABLE CONNECTOR TOE-IN-TYPE

George C. Thomas, Jr., Elizabeth, N. J., assignor
to The Thomas & Betts Co., Elizabeth, N. J.,
a corporation of New Jersey

Application April 29, 1947, Serial No. 744,556

10 Claims. (Cl. 285—6.5)

1

The invention relates in general to connectors for use with electric outlet box assemblies for securing cables to such box assemblies and constitutes a development of similar structures disclosed in my Reissue Patents 18,634, October 18, 1942, and 18,733, March 21, 1933.

It is known in the prior art to provide a connector including a tubular member fitted in a hole provided therefor in the wall of an outlet box, and into which tubular member is intruded a cable usually with a spirally wrapped metallic armour and secured by a shiftable clamping element of U-shaped form having its legs extending parallel to each other and to the length of the cable and passed through slots in the side of the connector for engaging the intruded cable.

In the prior art where the U-shaped form of clamps have been employed, it was found to be of advantage to cause the legs of the clamp to engage the cable parallel thereto and in transversely offset relation to the crown portion of the cable, especially in the case where the cable was encased in a corrugated metallic shield or armour which is apt to be crushed if too great a pressure is applied to its crown portion. In prior art devices the legs are caused to contact the cable at points about 90 degrees apart, or along lines each forming an angle of about 45 degrees to the line of thrust of the associated clamping screw. It is the intent herein to retain the advantages of this type of clamping means. The requirement that the pressure imposed on the armoured cable form an angle of about ninety degrees to the axis of the cable meant that for each different diameter of cable a different form of connector has to be custom fitted to each particular size of cable. Considering that many different sizes of cables are used in connection with outlet boxes, it is economically impossible to carry separate sized connectors for each size of cable to be used.

Accordingly, the primary object of the invention is to provide a standard one size form of connector, particularly in the shiftable clutch element thereof, which can clamp cables of widely different diameters and at the same time retain the advantages of the approximately ninety degree engagement with the cable, irrespective of its size, at least within limits.

Broadly this objective is obtained simply by changing the usual flat parallel relation of the clamping legs of the U-clamp to give them a toed-in or bowed-in relation towards the axis of thrust, so that at least in a general way the legs will engage the armour or other outside covering of

2

the cable at about the same relative points considered angularly, and at least to some extent independently of the diameter of the cable in use for the time being.

Various other objects and advantages of the invention will be in part obvious from an inspection of the accompanying drawings and in part will be more fully set forth in the following particular description of two forms of device embodying the invention, and the invention also consists in certain new and novel features of construction and combination of parts hereinafter set forth and claimed.

In the accompanying drawings:

15 Fig. 1 is an exploded view showing a preferred embodiment of the invention;

Fig. 2 is a sectional view taken axially through the device shown in Fig. 1 and shown in operative position securing an armoured cable to an outlet box;

20 Fig. 3 is a plan view of a stamped sheet metal blank from which the tubular member of the proceeding figures is formed;

Fig. 4 is a transverse sectional view taken on 25 the line 4—4 of Fig. 3 and showing a succeeding step in the formation of the embossed part of the tubular member;

Figs. 5 and 6 are each transverse sectional views taken on the line 5—5 of Fig. 2; Fig. 5 showing the 30 clamping element in distended position engaging a cable outline of large diameter, and shown in Fig. 5 in comparison with the outline of a cable of small diameter, and in Fig. 6 showing the same clamp more fully intruded and engaging a cable of relatively small diameter;

Fig. 7 is a plan view looking down on the clamping element of Figs. 1, 2, 5, 6 and 10, with the screw in position;

Figs. 8 and 9 correspond respectively to the 40 showings in Figs. 5 and 6 illustrate a two-part clamping element in distinction from the one part clamping element shown in the preceding figures; Fig. 8 showing in dotted and full lines two succeeding positions of the parts of the clamping element as they are assembled in position in the connector securing a cable of large diameter, and Fig. 9 showing the clamping element parts in their final operative position engaging a cable of relatively small diameter.

50 Fig. 10 is a plan view of a stamped metal blank from which the U-shaped member of Figs. 1, 5 and 6 is formed.

In the drawings and referring first to the preferred form of the invention shown in Figs. 1, 2, 5 and 6, there is disclosed the component ele-

ments of the connector herein featured and shown in operative position in Fig. 2, mounted in an outlet box A with one of the box walls provided with one of its usual punched-out outlet openings B dimensioned to receive the connector. The connector herein disclosed is designed to secure a cable C to the box and is arranged so that a pair of current carrying wires D encased in insulation E are in turn contained in a metal shield or armour F. The armour is of the conventional spiral groove form comprising one or more corrugations G forming a deep trough H between succeeding turns of the corrugation. The end of the cable to be intruded into the bore of the connector is usually prepared by cutting back its armour to form a squared off abutment end I and into this end is inserted bushing O designed to fit squarely against a stop therefore forming part of the connector herein featured.

In the showing of the small size cable in Figs. 6 and 9, the corresponding parts are similarly designed with the characters primed.

Referring to the showing in Figs. 1 and 2 for a description of the preferred form of the invention, there is disclosed a metallic connector 10 comprising a shell or tubular member 11 of somewhat cylindrical form and which is provided mid-length with an outwardly projecting angular corrugation 12 acting to form a stop for limiting the intrusion of the member 11 into the box hole B as is usual with such connectors. The end of the member 11 which projects outwardly from the box forms a barrel 13 on one side of the corrugation 12, and the portion which extends through the opening B and into the interior of the box forms an extension 14 exteriorly threaded as shown at 15. The threaded extension 14 is provided with a flat nut 16 bearing against the inner wall of the box A to receive the box wall between the nut and the corrugation and in general this part of the structure follows known practices in this respect. The bore 17 of the member 11 is partially closed at its inner end by a set of circumferentially spaced apart fingers 18 forming a bushing through which the conductor forming core portion of the cable may extend and which forms a stop for limiting the intrusion of the armour F and to form a closed joint with the abutment end I of the armour.

The upper side of the barrel is punched outwardly as hereinafter described in discussing the blank of Fig. 3, and the punched portion bent from the plane of the balance of the blank which is to form the barrel to form the offset embossment 19 constituting a support for the clamping means hereinafter described. The top surface 20 of the embossment is flat and inclined toward the adjacent open end of the barrel 13 at a small angle to the axis of the bore 17 and thus at a small angle to the axis of the cable C as best shown in Fig. 2. The embossment is provided centrally thereof with a screw hole 21 which extends therethrough perpendicularly to the top surface of the embossment. The portion containing the screw hole is drawn inwardly as more particularly shown in Fig. 4 to give the screw hole some material depth and is tapped to provide it with screw threads 22. The barrel 11 in the upper side thereof is provided with two long narrow slots 23-24 on opposite sides of the screw hole 21 and each extending for a material distance longitudinally of the length of the connector and thus of the cable intruded into the same.

The connector also includes a shiftable clamp

or clutch element 25 in the form of an inverted U and comprises a flat bight or crotch portion 26 overlapping the top surface 20. The U-shaped member includes two legs depending from the crotch portion in somewhat parallel relation and including a left leg 27 and a right leg 28 as viewed in Fig. 1.

The crotch portion 26 is provided centrally thereof with an unthreaded loose screw hole 29. The clamp element is disposed in position straddling the embossment 19 with the left leg 27 intruded through the slot 23 and the right leg 28 intruded through the slot 24 in both cases into bearing engagement with the cable C in the bore 17. A screw 32 is provided with a wide bearing head 33 for bearing on the crotch portion 26 and has its shank passed loosely through the unthreaded screw hole 29 and in screw threaded engagement with the long threaded hole 21.

The particularly novel feature of this disclosure is that the inner or free end portions of the legs, that is, the portions which are intended to engage the cable and herein marked respectively 30 and 31 are toed-in or bowed-inward towards each other as shown in Fig. 5 and Fig. 6. In the instant case each of the lower toed-in portions 30 and 31 forms an angle of about twenty-two and one half degrees with the axis of thrust a-b of the screw 32.

The lower cable engaging edges of the toed-in portion 30 and 31 are designed to engage the cable on opposite sides of its crown somewhat resembling known structure in this respect. In the case of the portion 30 of the left leg the lower edge is provided for the major part of its length with a smooth face 34 for engaging on top of the corrugation G and at its forward edge with a finger forming extension 35 somewhat V-shaped in side elevation and designed to intrude into one of the troughs H of the cable armour. The other portion 31 of the right leg 28 is similarly contoured but in reverse direction, that is, the forward portion of the edge provides a smooth face 36 and at its rear end is provided with the V-shaped extension 37 intruded into trough H as shown in Fig. 2. The extensions 35-37 are spaced apart longitudinally of the axis of the bore 17, and thus of the cable intruded therein, a distance equal to the spacing of the troughs between succeeding turns of the corrugation G or rather of the turns of the trough.

In order to provide some degree of flexibility between the crotch portion 36 and each of the legs 27-28, it is suggested that the four corners 55 of the crotch be notched or cut away slightly as shown at 38 in Fig. 7, so as to provide between the notches a corner hinge 39 between each leg and the crotch portion, with less cross sectional area of material in the hinge forming edges than would be present if the corner notches 38 were not made.

The line of thrust imposed by the screw 32 on the clamping member 25 is indicated in Figs. 5 and 6 by the line a-b passing through the axis of the large cable C and through the axis of the smaller cable C'. The lower portions 30 and 31 of the legs are inclined towards each other at an angle of about fifteen degrees with the thrust line a-b as indicated on Fig. 5.

Referring to the modified form of clamping element shown in Figs. 8 and 9, it will be understood that the structure in general resembles the one piece clamping element 25 except that it is made of two parts, 40 and 41, each of approximate

legs 42 and 43 in overlapping relation. The overlapping legs are provided with aligned loose screw holes 44 corresponding to the screw hole 29 in the preferred form and similarly designed to receive the screw 32 passed therethrough and into the screw hole 21.

In this form of the clamping element the toed-in portions of each leg, that is, the portion 45 of the left leg 40 and the part 46 of the right leg 41 each forms an angle of fifteen degrees with its axis of screw pressure along the thrust line $a-b$. Irrespective as to whether the single clamping member 25 or the two part clamps 40-41 is used, in either case the pressure edge or feet formed as indicated at 34-31 of Fig. 1 bears on the large diameter cable C respectively at points 47-48 disposed relative to the center or axis 50 of the cable to form in each case an angle of forty-five degrees with the line of thrust $a-b$ or a total included angle between the lines 50-c and 50-d of ninety degrees as shown in Fig. 5. The toed-in portions 30 and 31 each form with the axis of thrust $a-b$ an angle of twenty-two and one half degrees as indicated by the angles $e-f-a$ and $a-f-g$.

In the case of the cable C' of small diameter the pressure feet engage the cable at corresponding disposed points 47' and 48' and likewise form an angle of forty-five degrees from the center 50' of the small cable C' as indicated by the angles $h-50'-a$ and $a-51'-i$.

The blank as shown in Fig. 3 from which the tubular member 11 is formed comprised initially a long flat rectangular strip of thin bright rolled sheet steel, with rounded edges, die-punched to shape. There is formed at one short end a dove-tail recess K and at the opposite end a similarly shaped projection L, one fitted into the other to form in the finished member 11 an interlocking joint M shown in Fig. 1. This joint is not required to resist radially directed strains which might tend to open the joint as the member 11 is fitted somewhat snugly in the circular opening B in the wall of the box. The long flat joint illustrated is well adapted to resist any tendency of the member 11 to open at the joint M by reason of any relative longitudinal shifting of the parts on opposite sides of the joint.

Along one long side the blank is provided with four spaced apart lugs N subsequently bent as shown in Fig. 4 at right angles to the balance of the strip to form the stop fingers 18 of Fig. 2. The fingers are arranged in the finished tubular member in circumferentially spaced apart pairs to provide therebetween a pair of diametrically disposed clearances shown in detail in the companion application, and arranged to accommodate therebetween the opposite edges of the core portions of cables of different diameters. In the stamping operation which forms the blank of Fig. 3 the corrugation 12, the slots 23-24 and the then unthreaded screw hole 21 are formed at the same time the balance of the blank is shaped in its outline. Subsequently the embossment 19 is die punched into the inclined position shown in Fig. 4; the portion surrounding the hole 21 is drawn inwardly by appropriate die action to provide the requisite length to the tube as best shown in Fig. 4, and the hole so enlarged from the initial hole 21 is finally tapped to provide the necessary extent of threads 22, all before the blank is rolled into its final cylindrical form. The dove-tail ends are then interlocked to complete the tube 11 and the extension 14 thereof is externally threaded to provide the external nut engaging threads 15.

The clamp element 25 is also stamped from sheet steel at the time its screw hole 29 is formed and then the resulting blank as shown in Fig. 10 is bent conventionally into the U-form with its toed-in portions as disclosed in Figs. 5 and 6. The two-part form of clamping device shown in Figs. 8 and 9 are formed conventionally on a plate bending machine.

In operation and assuming that the connector 10 has been either presecured or subsequently secured to the outlet box, and that a cable, such as the large size cable, shown in Figs. 2 and 4, is intruded in place in the bore 17 with the abutment end I of its armour F engaging against the stop 18, the clamping element and screw are assembled as indicated in Fig. 2 if not already in place. Before pressure is applied by the screw on to the cable, the cable as a whole is rotated about its own axis until the forward projection 35 engages in a forward turn of the trough H, and the rear projection 37 engages in a portion of the trough spaced outwardly therefrom, that is to the right thereof as indicated in Fig. 2. The screw 32 is then advanced to force the coupling element inwardly. The force applied at the bottom edges of the clamping member, that is through surfaces 34 and 36 and through fingers 35 and 37 may be resolved into two components, one acting more or less conventionally transversely of the length of the cable, and the other acting longitudinally of the length of the cable and towards the stop 18 in such way as to force the armour end I into firm abutting relation to the stop 18, all as more fully described in the above identified copending application.

For ease in comparing the action of the bowed-in legs 27-28 of the clutch element 25, when cables of different diameters are used there is shown on the outline of the larger cable C, a cable C' of smaller diameter. Assuming that it is intended to clamp in the connector a cable of relatively smaller diameter such as is shown at C' in Fig. 6 the same clutch element 25 is used as was used with the larger cable. As the element 25 advances by reason of the screw load inwardly from the Fig. 5 position the free end portions 30-31 bear respectively on the outer edges of the slots 23 and 24. This causes each of the legs 27 and 28 to swing inwardly towards the thrust line $a-b$ swinging about their corner hinges 39. As the two legs move radially more and more inwardly, their points of contact likewise move both inwardly and towards each other from their maximum spread apart positions 47-48 towards their final contacting position engaging the smaller cable C' at the points 47' and 48' as shown in Fig. 6. The parts are so designed that in their final as well as in all intermediate positions the angles formed between the lines of thrust of the legs 27-28 intersect and form therebetween an angle of ninety degrees.

Referring to the two part clamping element shown in Figs. 8 and 9, it will be understood that in mounting it in place, the screw 32 is removed or almost so, and the two parts angled into the slots 23 and 24 as may be most convenient and as suggested by the dotted line showing in Fig. 8. The two parts when finally in position tend to assume the full line position shown in Fig. 8. The screw is then inserted through the then aligned loose screw holes 44, if not already in place, is advanced into threaded engagement with the screw hole 21 and finally tightened into position.

75 In the showing in Fig. 8 where a large size cable

is used the two-part clamping element corresponding to the one-piece clutch element 25 is relatively outset from the tubular member 11, and has its pressure edges or feet engaging the cable at the ninety degree offset points 47 and 48, in the same way as has been described for the preferred form of the invention. In the showing in Fig. 9 the two-part clamping element is relatively further intruded into the tubular member 11 to engage the smaller cable C' at corresponding ninety degree separated points 47' and 48'.

It is thus seen that irrespective as to whether a large or small diametered cable is used, and irrespective as to whether a one-piece or a two-piece clutch element is used, the bowed-in legs of the U-clamp will engage the outer surface of the cable at points about ninety degrees apart.

I claim:

1. In a connector for securing a spirally wound cable to an outlet box provided with a hole in a wall thereof, said connector including a tubular member provided with means for securing it to the hole in the box and adapted to receive the cable in its bore, a portion of the side of the member being offset to provide an embossment extending at an angle to the axis of the bore, having a threaded screw hole extending perpendicularly therethrough and provided on opposite sides of the embossment with a pair of longitudinally extending slots, means for clamping the cable to the member and including a clamping element of inverted U-shape straddling the embossment and having its legs intruded through the slots and into the bore of the member, the intruding cable engaging ends of the legs in the portions thereof designed to intrude into the bore, being bowed-in towards each other to form an acute angle therebetween and fashioned for engaging the adjacent side of the cable along parallel lines on opposite sides of its crown portion irrespective of the diameter of the portion of the cable engaged thereby, and said clamping means including a headed screw passed loosely through the crotch portions of the clamping element, disposed to have its head bear thereon and extending in threaded engagement through the threaded screw hole.

2. A blank substantially rectangular in plan and initially formed from sheet metal, provided at one short end with a dovetail recess and at its other short end with a corresponding shaped projection, one long edge of the blank provided with a pair of legs adapted to be bent to form a stop for the bore of the finished article, said blank provided with a longitudinally extending corrugation and between the corrugation and the other long side with a pair of transversely extending slots and a screw hole located between the slots.

3. A one-piece blank for forming a cable connector substantially rectangular in plan and formed of sheet metal, said blank provided with a longitudinally extending corrugation and between the corrugation and one of the long sides with a pair of transversely extending slots, the portion of the metal between the slots forming an embossment extending transversely of the blank and for the most part offset from the plane containing the balance of the blank, merging at its inner end into the corrugation and at its outer end into said long side, said blank except for its embossment being initially flat and said embossment provided with a threaded screw hole.

4. The blank defined in claim 3 in which the portion of the embossment containing the screw

hole is a short internally threaded tube whose axis extends at an obtuse angle to the plane of the blank and is internally threaded to provide a long bearing for a screw.

5. A connector including a tubular member having a pair of circumferentially spaced-apart slots, a clamping member of inverted U-form having a crotch and two legs extending from the crotch and passing through the slots, each leg being shiftable relative to the crotch along the bends formed between the crotch and each leg, screw operating means connecting the crotch and member and providing a line of thrust passing between the slots and substantially through the axis of the member, said slots being each spaced about twenty-two and one-half degrees arc distance from said line of thrust, each leg formed of two integrally connected parts with the lower parts toed-in towards each other and towards said line of thrust and extending through the slots, the lower part of each leg initially forming an angle of about fifteen degrees with the line of thrust.

6. A connector including a tubular member having a pair of circumferentially spaced-apart parallel slots each forming a flat parallel guide surface at its outer side edge, a clamping element of inverted U-form including a crotch and two legs extending from the crotch and inserted in the slots, manually actuated operating means connecting the crotch and member for advancing the clamping element into clamping position and providing a line of thrust passing between the two slots, each leg movable relative to the crotch, the inner portion of the legs which extend into the member being inclined towards each other and to the line of thrust, the maximum distance between the inclined inner portions of the legs being not less than the arc distance measured between the slots, the outer side of each inclined inner leg portion bearing on its associated guide surface and reacting therewith on the advance of the operating means to cause the legs to shift relative to the crotch still further inwardly towards the line of thrust.

7. The connector defined in claim 6 and in which the bend formed between one leg and the crotch is cut away at least at one end to reduce the cross section of material in that bend.

8. The connector defined in claim 6 and in which the clamping element is formed of two separable L-shaped parts, each part including one of the legs and a portion of the crotch with a bolt hole in the crotch portion, the two parts operably designed when separated to facilitate the insertion of each of their legs in its associated slot, and the crotch portions disposed when in overlapping relation to have the two bolt holes in registry to facilitate insertion of the operating means passed therethrough and said opening means passed through said aligned bolt holes.

9. A connector including a tubular member having a bore fashioned to receive therein cables of different diameters, said member provided on one side thereof with a pair of parallel slots, a clamping member of inverted U-form having a crotch portion and two legs extending therefrom and with their inner ends intruded through the slots and into the bore to engage the cable for the time being in the bore at points thereon having an arc distance substantially equal to about forty-five degrees, screw means reacting between the crotch of the clamping member and the tubular member to advance the legs into clamping position and providing a line of thrust passing

between the slots and substantially through the axis of the bore, the portion of the member outlining the edges of the slots forming guide surfaces, the guide surfaces each forming an angle of materially less than forty-five degrees with the line of thrust, the inner ends of the legs forming toed-in portions inclined towards each other and to the line of thrust and bearing on the guide surfaces and reacting thereon to cause the toed-in portion to approach the line of thrust as the screw means is advanced.

10. In a device of the class described, the combination of a tubular member having a pair of longitudinally extending parallel and circumferentially spaced-apart slots, a spirally wound cable inserted in the member and having a corrugation with an exposed spiral trough between adjacent turns of the corrugation, a clamping member of inverted U-form and having two legs extending through the slots, a screw reacting between the members, providing a line of thrust extending between the slots and through the axis of the tubular member, the portion of the legs within the tubular member being inclined towards each other and to the line of thrust, the free cable engaging

edges of the legs being for the most part flat for engaging the cable and each edge provided with a projection depending therefrom, said projections being spaced apart lengthwise of the cable and fashioned for engaging in the trough at spaced-apart points thereof and said line of thrust inclined to the axis of the tubular member to cause said projections to bear axially of the cable on the portion of the corrugation in advance of the projections.
